UNITED STATES PATENT OFFICE.

LOUIS LANE, OF HABANA, CUBA.

WINDOW.

1,392,183.

Specification of Letters Patent. Patented Sept. 27, 1921.

Application filed September 18, 1919. Serial No. 324,522.

To all whom it may concern:

Be it known that I, LOUIS LANE, a citizen of the United States, and at present residing at Habana, Cuba, have invented a new and Improved Window, of which the following is a description.

My present invention relates to windows employing sliding sashes, and more particularly to windows in which the sashes have line contact with the guide members engaged thereby on the window frame.

The invention has for an object to provide a novel construction and relative arrangement of the jamb members of the frame and the sash members to insure the line contact and be capable of embodiment generally in windows having sliding sashes.

The invention has for a further object to provide meeting rails of novel form arranged to insure line contacts therebetween when the sashes are in the closed position.

More specifically, the invention has for its object to provide an embodiment of the invention reflecting important considerations with respect to simplicity and durability and the convenience of installation and the partial or complete disassembling of the same for repairs or the like.

The invention consists in a window having the novel features hereinafter particularly described and claimed.

Reference is to be had to the accompanying drawings forming a part of this specification, it being understood that the drawings are merely illustrative of one example of the invention.

Figure 1 is a transverse vertical section of a window embodying my invention;

Fig. 2 is a horizontal section on the line 40 2—2, Fig. 1;

Fig. 3 is a detail view in horizontal section showing a modified form of one of the vertical side members of the window frame; and

Fig. 4 is a similar view illustrating a further modification of one of the vertical side members.

In carrying out my invention in accordance with the illustrated example, a metal window frame is provided comprising a top bar or frame-head 10, a bottom bar or sill 11, and vertical side bars or jambs 12 and 13. The form of window shown in the illustrated example of my invention is the panel type in which there are side jambs and in-

termediate jambs and one or more of the sashes in the window may be sliding and one or more fixed. In the form shown in Figs. 1 and 2, the intermediate jamb 13 is hollow, composed of two channel bars united face to face to form a tubular jamb. The jambs have novel guide members as will appear for the upper and lower sashes 14, 15. For illustration, the sashes are shown as of the counterbalanced type, as distinguished from the counterweighted type. A chain 17 is secured at one end to a bracket or plate 16 on lower sash 15, said chain running over a pulley 18 and here shown as secured by a screw 19 to the horizontal flange of an angle bracket 20 on upper sash 14 and provided with set nuts 20, 21 above and below the bracket.

Parting strips 22 are provided in the form of channel bars secured to the jambs 12, 13 by screws 23 or other suitable fastening means. Inner stops 24 are Z-shaped in cross section and secured by screws 25 or the equivalent. Similarly, outer stops 26 are employed, Z-shaped in cross section, one flange of each of which is secured by screws 27 or the like to the jamb. To add to the weather-tight qualities of the window, similar bars 28, 30, Z-shaped in cross section, are similarly placed across the frame-head 10 at the outside, and across the sill 11 at the inner side, and secured by screws 29, 31, respectively, to be in contact with the sash frames when closed. Screws 25, 27 securing the stops to the channel bar jambs 12, 13 take into lateral flanges 33 directed laterally outward on said jambs and in the case of the intermediate jamb 13 the two opposed U-shaped channel members forming the same have their flanges 33 directed laterally outward on said jambs and in the case of the intermediate jamb 13 the two opposed U-shaped channel members forming the same have their flanges 33 united by suitable screws 25^a. The screen at the bottom may be held in any approved manner. Inner and outer stops 24, 26 and the cross bars 28, 28^a and 30 have slots 32 therein through which the fastener screws are passed, the slots permitting said stops and cross bars to be adjusted toward and from the sashes to effect the desired tightness of joint between the sash members and the window frame members.

Each sash side member is composed of a

channel bar 34 having a narrow flange 35 and a wider flange 36, the edges of the latter extending into channels 41 formed by the stops 24, 26 and the adjacent sides of the channel jambs, the inner flanges 24^a, 26^a of the respective stops being disposed toward the sides of said jambs and presenting narrow throats snugly accommodate the wider flanges 36 of the sash frame members, and said throats may be made wider or narrower by adjusting the stops; said arrangement serves to produce an effective guiding of the sash in the window frame. An important factor entering into my improved window resides in the relative form of the sash frame members 34 and the guiding members on the window frame engaged by the sash frame members. It will be observed that the inner surface of a flange 36 and the opposed surface presented by the side of a jamb flare, the result being produced by one or both of said surfaces being made oblique; in the illustrated form the flanges 36 taper to give the desired result and it will be seen that the line contact with the channel bar jambs 12 and 13 is therefore along a line at the adjacent angles presented by said jambs, that is to say at the base of the flanges of said channel bars. There is essentially a line contact produced also between the outer surfaces of the flanges 36 and the inwardly disposed flanges 24^a, 26^a of the stops. Similarly, a line contact is effected between the shorter flanges 35 of the sashes and the channel parting strips 22, for which purpose the members of the parting strips taper outwardly. It is to be noted that the flanges of the parting strips 22 are directed outwardly and the outer surfaces are outwardly converged, also the flange 35 tapers and the line contact is at the base of the flanges on strips 22. The bottom cross bars or strips 28^a, 30 and the top cross strip 28 similarly make a close contact when engaging the cross bars of the sash frames, the top and bottom channel rails and the meeting rails of which are formed as next described.

The meeting rails 37 of the sashes are in the form of channel bars presenting at the outside comparatively narrow flanges 38 and at the inside opposed wider flanges 39. The flanges 39 are curved laterally as at 40 to overlap in the plane of the parting strips 22 and they present opposed curved surfaces so that the edges of said flanges 30 will produce line contacts to effect a tight engagement of the meeting rails. The top bar or rail 37^a of the outer sash is channeled corresponding substantially with the meeting rails 37 and presenting a narrow flange 38^a and a wider flange 39^a which curves laterally inward at its free edge as at 40^a, presenting a convex surface to engage with the lintel or top bar 10 of the window frame by

substantially a line contact, said top bar 10 having the inner and outer portions in different horizontal planes and joined by an oblique portion 10^a with which the curved portion 48^a contacts. The top bar 28 makes a close contact with the flange 38^a, the contact being insured by the adjustment of said top bar by screws 29. Similarly, the bottom rail or cross bar 37^b of each lower bar 15 is in the form of a channel bar presenting a narrow flange 38^b to be engaged by the bottom cross strip 30 and a wider flange 39^b, the lower portion of which is curved as at 40^b to contact with the oblique portion 11^a of the sill 11.

The above-described construction, it will be seen, provides a secure retention of the sashes, an effective guiding thereof in the window frame with the desired close joints between the sashes and frame parts, and the construction insures strength and durability and involves few parts of minimum simplicity.

When the sash at one side of the intermediate jamb 13 is fixed, instead of sliding, said jamb may be arranged as in Fig. 4 in which a channel jamb member 13 as described with flanges 33 is provided at one side with stops, the outer stop 26 and one of its securing screws 27 being indicated in said figure. The fastening screws serve to secure to the channel jamb member 13 a plane plate 42 closing the channel, the securing screws passing through said plate and the flanges of said channel jamb member. The adjacent channel bar 34^a of the sash 15^a has flanges 35^a, 36^a which may be of equal length, the said channel bar being secured by screws, one screw being indicated at 44. A flat plate 43 secured by a rivet 44^a or other permanent fastening means may be provided, disposed between the flanges 35^a, 36^a.

The form shown in Fig. 3 provides for an enlarged intermediate jamb, the channel jamb members 13 having interposed between their flanges 33 thereof a channel bar 45 secured to the flanges 33 by suitable fasteners 46.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

1. A window including a window frame and a sliding sash therein having its frame formed of channel bars, presenting side flanges of unequal width, said window frame having guide means for the narrower flanges of the sash and with which said narrower flanges contact at their outer surfaces, the

end edges of said narrower flanges being disposed toward the opposed vertical surface of the frame; and said frame presenting channels receiving the edge portions of the wider flanges of the sash.

2. A window including a window frame and a sliding sash therein having its frame formed of channel bars, the flanges of which are of unequal width, said window frame having guide means for the narrower flanges of the sash and presenting channels receiving the edge portions of the wider flanges of the sash; together with means to adjust a side wall of the frame channels to vary the width of said frame channels.

3. A window including a window frame and a sliding sash therein having its frame formed of channel bars, the flanges of which are of unequal width, said window frame having guide means engaged by the narrower flanges of the sash and presenting channels receiving the edge portions of the wider flanges of the sash, one side surface of said wider flange and the opposed channel surface having a flaring relation and effecting line contact therebetween.

4. A window including a window frame and a sliding sash therein having channel frame bars presenting flanges of unequal width, Z-shaped stops forming with the opposed side surfaces of the jamb, channels laterally inward of the stops, the wider flanges of the sash extending into said channels, said stops presenting members disposed laterally inward toward and terminating adjacent to said wider flanges.

5. A window including a window frame and a sliding sash therein having channel frame bars presenting flanges of unequal widths, stops forming with the opposed side surfaces of the jamb, channels laterally inward from the stops, the wider flanges of the sash extending into said channels and tapering outwardly and making line contact with those walls of the channel opposite said stops at the inner edges of said walls.

6. A window including upper and lower sliding sashes having meeting rails provided with flanges at their adjacent sides, said flanges overlapping and being curved transversely at their overlapping terminal portions, each terminal portion presenting a concave surface to the contacting edge of the other flange.

55 7. In a window, a sliding sash, the bottom sash bar of which is in the form of a channel bar, the lower terminal portion of the outer flange of which channel bar extends below the opposite flange and is deflected laterally outward from the general plane of said outer flange to present an integral member having a convex under surface for contact with a sill.

8. In a window, a sliding sash, the bottom sash bar of which is in the form of a chan-

nel bar, the lower terminal portion of the outer flange of which channel bar extends below the opposite flange and is deflected laterally outward from the general plane of said outer flange to present an integral 70 member having a convex under surface for contact with a sill; together with a sill presenting an oblique surface with which said convex surface is adapted to make contact in the closed position of the sash.

9. In a window, upper and lower sliding sashes, the lower sash having the bottom cross bar thereof channeled, said bar presenting flanges of unequal widths, the wider flange being curved outwardly, and a window frame having a bottom cross bar or sill presenting an oblique surface in position to receive the contact of said curved portion on the sash distant from the edge of said curved portion.

10. In a window, upper and lower sliding sashes, the upper sash having a top cross bar of channel form presenting an upwardly directed flange at the inner side extending to a height above the outer flange 90 of the channel bar, and curved laterally at its upper portion from the general plane of the bar to present an outer convex surface for contact with the head of the window frame.

11. In a window, upper and lower sliding sashes, the upper sash having a top cross bar presenting an upwardly directed flange deflected laterally in curved form from the general plane of said flange at its upper 100 portion; together with a window frame presenting a top cross bar having an oblique portion with which the laterally deflected portion of said flange is adapted to contact.

12. A window including a window frame 105 the jambs of which are composed of channel bars, said channel bars presenting at opposite sides thereof flanges, forming the sides of the channel, the terminals of said sides being directed laterally outward at angles to the planes of said channel sides, and stop beads secured to said laterally directed terminals.

13. A window, including a window frame, the jambs of which are composed of channel 115 bars, said channel bars presenting at opposite sides thereof flanges, forming the sides of the channel, the terminals of said sides being directed laterally outward at angles to the planes of said channel sides, and stop beads secured to said laterally directed terminals, said stop beads having lateral flanges at the inner sides thereof disposed toward the respective sides of the channel bar jambs, forming with said sides, channels outside of the jambs.

14. A window, including a window frame the jambs of which are composed of channel bars, said channel bars presenting at opposite sides thereof flanges, forming the 130

- sides of the channel, the terminals of said sides being directed laterally outward at angles to the planes of said channel sides, and stop beads secured to said laterally directed terminals, and stop beads secured to said flanges, said stop beads having lateral flanges at the inner sides thereof disposed toward the respective sides of the channel bar jambs forming with said sides channels outside of the jambs; together with sliding sashes each presenting a flange accommodated in the respective channels between the stop beads and the sides of the channel bar jambs.
15. A window including a window frame and vertically sliding sashes therein, the frame members of which are in the form of channel bars presenting each a wider and a

narrower flange, and members on the window frame jambs forming vertical channels 20 into which the wider flanges on the side bars of the sash extend, the wider flanges of the top bar of the upper sash and that of the bottom cross bar of the lower sash being deflected laterally and the top and bottom cross bars of the window frame presenting to said deflected portions, obliquely disposed surfaces with which said deflected portions are adapted to respectively contact in the closed positions of the sashes, the 25 wider flanges of the meeting rails terminating in laterally curved portions that overlap and contact with each other in the closed positions of the sashes.

LOUIS LANE.
